PAINT BRUSH

William Wagner, Absecon, N.J.

Application February 28, 1958, Serial No. 718,236

2 Claims. (Cl. 15—248)

This invention relates to improvements in paint brushes and, more specifically, the invention pertains to the provision of a drip cup or receptacle for receiving paint from the paint brush when the same is held in an inverted position.

One of the primary objects of this invention is to provide in a paint brush means intermediate the brush bristles and handle for receiving paint from the bristles when the brush is inverted for overhead painting.

Another object of this invention is to provide in a paint brush a receptacle disposed intermediate the brush bristle and handle, the receptacle receiving drippings from the bristles when the brush is inverted, the receptacle having flexible side walls which are flexed for extruding the accumulated paint therein to return the paint to the bristles.

A further object of this invention is to provide a paint brush of the type referred to supra, the brush having means thereon for receiving paint runback from the bristles when painting overhead, the means being operable to return the runback paint to the bristles with a consequent reduction in waste paint and the resulting reduction of material costs.

A still further object of this invention is to provide a paint brush with a compartment filled with an absorbent material, the compartment being formed of side walls formed of a plastic material being sufficiently flexible to permit the same to be turned inside out to fully expose the absorbent material thereby facilitating the removal thereof from the brush.

Still another object of this invention is to provide a paint brush of the type generally described above, together with means for insuring the connection of the side walls of the container to the paint brush head to prevent the accidental and/or inadvertent slippage thereof therefrom during a painting operation.

This invention contemplates, as a still further object thereof, the provision of a paint brush of the type generally described above, the paint brush being non-complex in construction and assembly, inexpensive to manufacture and durable in use.

Other and further objects and advantages of the instant invention will become more evident from a consideration of the following specification when read in the light of the annexed drawing, in which:

Figure 1 is a perspective view of a paint brush constructed in accordance with the present invention;

Figure 2 is an exploded perspective view of the paint brush illustrated in Figure 1;

Figure 3 is a detail cross-sectional view taken substantially on the vertical plane of line 3—3 of Figure 1, looking in the direction of the arrows;

Figure 4 is a detail cross-sectional view taken substantially on the vertical plane of line 4—4 of Figure 3, looking in the direction of the arrows; and,

Figure 5 is a fragmentary detail cross-sectional view, partly in plan view, Figure 5 being taken substantially

2

on the horizontal plane of line 5—5 of Figure 3, looking in the direction of the arrows.

Referring now more specifically to the drawing, reference numeral 10 designates, in general, a paint brush constructed in accordance with the teachings of this invention. The paint brush 10 is seen to comprise an elongated handle 12 having an elongated substantially rectangular base 14 integrally connected with one end thereof and extending transversely with respect thereto. The base 14 receives the threaded ends 16 of a pair of elongated screws 18 provided with enlarged heads 22 having threads 24 extending inwardly from the upper ends thereof. An elongated substantially rectangular plate 26 is superposed over the headed ends 22 of the screws 18, the plate having a pair of longitudinally spaced apertures 28 extending transversely therethrough adjacent each end thereof, respectively. The apertures 28 are coaxially aligned with the screws 18.

To serve a purpose to be described below, the plate 26 is provided with a plurality of laterally and longitudinally extending struts 30.

Disposed in juxtaposition with respect to the plate 26 is a substantially hollow rectangular bristle box 32 having one end of a plurality of paint brush bristles 34 fixedly secured therein in the conventional manner. The box 32 extends longitudinally of the plate 26 and is provided with an opening 36 adjacent each of its respective ends through which extend screws 38 for engagement with the internal threads 24 of the head 22 formed in the screw 18.

Reference numeral 40 designates a substantially rectangular casing formed of rubber or of any other suitable flexible plastic material, the casing 40 having a pair of opposed open ends. One end of the casing 40 is bonded or otherwise secured to a continuous peripheral flange 42 formed of an elastic material such as, for example, rubber, the flange 42 being provided at its outer end with an integral inwardly extending lip 43, which serves a function to be described below.

As is clearly seen in Figures 2, 3, 4 and 5, the outer ends of the struts 30 are integrally formed or otherwise rigidly secured to the inner side of a continuous substantially rectangular flange 44. In accordance with this invention, the lip 43 is hooked over the outer end of the flange 44 to prevent the accidental or inadvertent displacement therefrom of the resilient flange 42. The other open end of the casing 40 is secured to the base 14 as by nails or tacks 45.

As is seen in the figures, the struts 30 hold the flange 44 in spaced relation relative to the plate 26 to form 50 passages 48 therebetween.

The handle 14, casing 40, plate 26 and flange 44 define a substantially hollow compartment 46 adapted to receive paint absorbent material 49, which may be formed of sponge rubber or of any other suitable material.

The brush 10 is manually operated in the conventional manner, the members making up the compartment 46 possessing sufficient rigidity to prevent the turning of the bristles 34 relative to the handle 12. However, the paramount advantage of the brush of the instant invention over conventional paint brushes becomes most evident when engaged in painting overhead. Under such conditions, the brush 10 is inverted and the bristles 34 thereof may be saturated to their maximum paint retaining capacity and, as is now obvious, any paint runback or drip towards the handle 12 due to gravity will pass from the bristles 34 through the passages 48 and into the compartment 46 where the same is absorbed by the absorbent material 49.

At any time after paint begins to accumulate within the casing 40 the operator may invert the brush 10 from the positions thereof illustrated in Figures 1 through 4, inclusive, and through the simple expedient of squeezing the casing 40 the paint accumulated in the compartment

ment 46 and in the absorbent material 49, will be extruded through the passages 48 back upon the bristles 34.

The sponge rubber or other absorbent material 49, in addition to absorbing paint accumulated within the compartment 46 during overhead painting, serves still another function. For example, when the brush user changes from overhead painting to general painting, that is, for example, to wall painting, the paint accumulated within the compartment and absorbed by the material 49 would have a tendency to leak back through the openings or passages 48 which would cause undesirable drip and paint wastage. The absorbent material prevents this from occurring.

Through the provision of a flexible casing such as designated at 40 and the flexible flange 42, the user of the paint brush 10 may detach the lip and flange 42, 43 from the flange 44 and turn the casing inside out. The absorbent material 49 may now be removed and the inner side of the casing cleaned in the event the user contemplates a change in the color of the paint being used. Additionally, and by virtue of this brush construction, the brush bristles 34 may be readily replaced through the simple expedient of removing the screws 38 and replacing the bristle unit.

Having described and illustrated one embodiment of this invention in detail, it is to be understood that the same is offered merely by way of example, and that this invention is to be limited only by the scope of the appended claims.

What is claimed is:

1. A paint brush comprising a handle having a base at one end extending transversely thereof, a bristle box support plate, said bristle box support plate including a plurality of struts projecting laterally therefrom and a first flange rigidly connected to the outer ends of said struts in spaced relation relative to said plate to form paint runback passages therebetween, means fixedly securing said plate to said base in spaced relation relative thereto, a bristle box having a plurality of bristles projecting from a side thereof, means fixedly securing said bristle box to said plate, a flexible casing extending between and across said base and the adjacent side of said plate, said casing including a flexible second flange fixedly secured to one end of

5

said casing and adapted to engage around said first flange, said second flange including a lip adapted to engage over an end of said first flange to releasably secure said first flange with said second flange, means fixedly securing the outer end of the casing to said base, and absorbent material disposed within said casing and occupying the entire space between adjacent sides of said base and said bristle box support plate.

2. A paint brush comprising a handle having a base at one end thereof extending transversely thereof, a bristle box support plate, said plate having a plurality of struts projecting laterally therefrom, a continuous flange surrounding said plate and connected with said struts in spaced relation relative to said plate to form a plurality of paint runback passages, means rigidly securing said plate to said base in spaced relation relative thereto, a bristle box having a plurality of bristles projecting laterally therefrom, means releasably connecting said box to said plate, an elongated casing having a pair of opposed open ends, means fixedly securing one of said open ends to said base, a flexible flange fixedly secured to said casing adjacent the other open end thereof, said second flange releasably engaging around said first flange, said second flange having a lip integral therewith for releasable engagement over an end of said first flange to prevent inadvertent disengagement of said second flange from said first flange, and removable paint absorbent material disposed within said casing and extending between adjacent sides of said plate and said base, said second flange being detachable from said first flange whereby said casing may be turned inside out to facilitate the removal and replacement of said absorbent material.
